SIZING DEVICE FOR WINDING MACHINES

Furman G. Carroll, Media, Pa., assignor to American Viscose Corporation, Wilmington, Del., a corporation of Delaware

Application June 6, 1942, Serial No. 446,095

4 Claims. (Cl. 242—37)

This invention relates to winding machines and more particularly to an improved device for arresting the operation of the machine when the package being wound reaches a predetermined size.

The present invention is particularly directed to winding machines of the type generally disclosed in United States Patent No. 801,941 to Wardwell, wherein the yarn is wound upon a supporting element, such as a core, mounted upon a rotating spindle, the yarn being traversed longitudinally of the core by a thread guide that bears against the surface of the winding, and which swings away from the spindle as the wound package increases in size. The form of device for stopping the winding machine generally employed with this type of winding machine and shown in the Wardwell patent has the disadvantages of being somewhat slow-acting and of increasing the pressure of the thread guide against the surface of the winding as the package approaches the predetermined size to which the stopping device has been set. The slow-acting characteristic of the device results in wound packages of non-uniform weight but, what is important, the increased pressure of the package during actuation of the stopping device deforms the wound package.

It is an object of the invention to provide a novel form of device for automatically stopping the winding when the package reaches a predetermined size which device avoids the exertion of undue pressure of the guide against the package. Another object is to provide such a device which is simple in character and which may be readily attached to standard machines without altering the structure thereof. Another object is to provide such a device which is adapted to cooperate with the mechanism for stopping the device automatically upon breakage or exhaustion of the supply of the yarn or strand being wound. A further object is to provide a device which is adjustable in character so that a package of any desired size may be obtained upon the machine or machines to which the attachment is applied. Other objects and advantages will appear from the drawing and description thereof.

In the drawing, illustrative of the invention,

Figure 1 is a front elevational view of a conventional type of winding machine showing the present invention applied thereto.

Figure 2 is a side elevational view of the winding machine shown in Figure 1.

Figure 3 is a perspective view of a detail.

While the invention will be described herein-after in relation to a particular type of conventional winding machine, it is to be understood that it is not limited to application thereto. In the description, the conventional parts of the winding machine will first be described and this will be followed by a description of the parts which constitute the present invention.

10 Referring to the drawing, reference numeral 2 designates the fixed main frame of the machine. At the top of frame 2, a rotating spindle 3 is journaled in suitable bearings and is adapted to be driven by means of a belt pulley or other suitable mechanism (not shown). The spindle is adapted to receive a cone or cop tube 4 upon which the package 5 is to be wound.

20 A shaft 6 is journaled in the frame 2 and extends in a direction parallel to the winding spindle 3. This shaft 6 is connected to the spindle and is driven therefrom by suitable means, such as gears, a belt and pulleys, or sprockets and chain (not shown). The shaft 6 also carries a helical grooved cam 7 for rotation therewith.

30 A traverse frame 8 is pivotally mounted upon the shaft 6 upon which it is suitably balanced such as by the counterweight 9. This traverse frame 8 is provided with a backing plate 10 and a porcelain bail 11 may be rotatably supported on a wire 12 whose depending legs adjacent the ends of the bail are suitably fastened within recesses in the plate 10 by means of set screws 13. The traverse frame 8 is constructed to provide a horizontal groove through which a traverse bar 14 may reciprocate. A thread guide 15, whose upper end is adapted to press lightly against the package being wound is fastened to 40 one end of the traverse bar 14 for reciprocation therewith. The other end of the traverse bar 14 is provided with a head 16 having a depending pin or roller 17 adapted to engage the groove in the helical cam 7. As the package builds up, 45 it gradually swings the traverse frame 8 away from the spindle 3 and the traverse frame is prevented from swinging back toward the spindle by means of a lever 18 having one end fastened thereto at 19 and the other end engaging within 50 a groove formed underneath a segment 20 which is pivotally fastened to the main frame 2 at 21.

The operation of the winding machine is controlled by a starting lever or handle 22, mounted on one end of a rotatable rod 23, supported in bearings at the top of the main frame 2. The

opposite end of the rod 23 carries means for operating a clutch or similar device (not shown) to control the operation of the spindle 3 and the other parts of the machine driven therefrom. A lever 24 is mounted adjacent the starting lever 22 on the rod 23 so that it rocks therewith. One end of lever 24 is normally biased in a counter-clockwise direction by a spring 25 fastened to the frame 2 and is provided with a braking means 26 which is adapted to press against the spindle 3 and to stop the rotation thereof when the lever 22 is in the stop position in which position the clutch or other device for operating the spindle 3 is disengaged. The other end of the lever 24 is formed as a curved arm having a hook 27 at its end. When the starting lever 22 is in operating position, in which the clutch is engaged with the spindle 3 and the brake is lifted therefrom (as shown in Figure 1), the hook 27 engages another hook 28 secured to or constituting part of the pivoted segment 20. The machine may be maintained in running position by setting these hooks 27 and 28 in opposition to the spring 25 which otherwise would tend to set the brake and to swing the starting lever 22 into the stop position.

In operation of the machine, the yarn passes first through a tension device 29 over the guide 30, under a break or exhaustion detector 31, over the porcelain bail 11 and through the traverse guide 15 to the package. The break detector 31 comprises a device pivotally mounted at 32 upon segment 20. The device is composed of two arms 33 and 34, one of which 33 extends toward a wheel 35 having numerous projections or ridges 36 thereon mounted upon the cam shaft 6 for rotation thereby. The other arm 34 is bent to form a horizontal extension 37 adapted to ride upon the yarn and along which the yarn may traverse to a certain extent. The extension 37 may be bent at the end to form a hook 38 to prevent the yarn from accidentally slipping out of engagement therewith. The first arm 33 is of such length and the entire detector device 31 is so balanced that upon breakage of the yarn, the device swings in a clockwise direction to bring arm 33 into the path of the projections 36 upon the rotating wheel 35 which in turn forces the segment 20 in a counterclockwise direction sufficiently to release the two hooks 27 and 28 and thereby permit the spring 25 to throw the starting lever 22 into the stop position to apply the brake and disengage the clutch. A projection 39 is provided to limit the clockwise motion of the arm 34.

The parts of the machine so far described are conventional and constitute no essential part of this invention except as will appear hereinafter. The arm 33 of the end breakage detector is independently pivotally supported at 40 on the pivotal mounting 41 upon which the other arm 34 is fixedly secured. A screw 42 secured to the pivotal mounting 41 of the end breakage detector serves as a rest for the arm 33 to limit its counterclockwise motion with respect to the pivotal mounting 41 of the end breakage detector. A stop 43 suitably mounted on the main frame 2 serves to limit the clockwise pivotal motion of the arm 33 with respect to the mounting 41.

A pendant member 44 which is independently pivotable with respect to the segment 20 may be arranged to pivot upon the same axis 32 as that upon which the end breakage detector mounting 41 pivots. The pendant member 44 is preferably so constructed as to hang the position

shown in Figure 1. The dependent arm of this member 44 is provided with an extension 45 at right angles thereto. The upper end of the member 44 is arranged to be engaged by a part of the traverse frame.

As shown, a right-angle bracket 46 is provided to be supported by the bail wire screw 13. An ear 47 is adjustably supported upon the right-angle bracket 46 by means of a suitable screw 48 so that a mere adjustment of the ear through a desired angle serves to vary the size of package obtained at the time the stopping of the machine is effected by engagement of the member 44 by the ear 47.

As will be recognized from a study of the drawing, the winding machine is stopped upon swinging of the arm 44 by the ear 47 so that the extension 45 brings the arm 33 into engagement with the projections 36 on the wheel 35.

Because of the light weight of the member 44, a very light pressure is needed in order to bring the projection 45 into contact with the arm 33 and then the arm 33 into engagement with the projections on the wheel 35. In addition, while the sizing stop mechanism of this invention cooperates with the end breakage stop, the provision of the independently pivotable arm 33 for cooperation with the extension 45 serves to bring the machine to a stop when the proper size package is obtained without seriously changing the tension of the yarn being wound as it passes under the extension 37 of arm 34.

Besides the adjustment that is possible by merely changing the angular relationship of the ear 47 to the bracket 46, further adjustment may be accomplished by replacing the ear itself by ears of different sizes. From the description of the device, it is apparent that it is quick in action and involves only a slight amount of pressure for a relatively short time during the last part of the winding. It is simple in character, readily attachable to any winding machine and is easily adjusted.

In the present specification and claims, the term "package" is used in a general sense to indicate any form of wound mass and the term "yarn" is intended to designate any kind of strand material whether textile or otherwise.

While a preferred embodiment of the invention has been disclosed, it is to be understood that such changes and variations may be made as do not depart from the spirit and the scope of the invention as defined by the appended claims.

I claim:

1. In a winding machine, a winding spindle, a traverse mechanism, means for swinging said spindle and traverse mechanism relative to each other about an axis substantially parallel to that of the spindle as the winding proceeds, means for stopping said machine automatically comprising an arm arranged to be swung into engagement with an operating member of said machine to initiate the operation of said stopping means, a pivotally mounted pendant member having one end arranged to be engaged by a part of said traverse mechanism substantially only after a predetermined size of package has been attained and the other end arranged after such engagement, to move said arm to initiate the operation of said stopping mechanism.

2. In a winding machine, a traverse frame, means for stopping said machine automatically comprising an arm arranged to be swung into engagement with an operating member of said machine to initiate the operation of said stop-

ping means, a pivotally mounted pendant member having one end arranged to be engaged by a part of said traverse mechanism substantially only after a predetermined size of package has been attained and the other end arranged after such engagement, to move said arm to initiate the operation of said stopping mechanism.

3. In a winding machine, a winding spindle, a rotatable element, means for stopping said machine, a member having an arm movable into engagement with said element to initiate said stopping means and having a second arm in engagement with the running course of yarn being wound, said member being normally withheld from movement to initiate operation of the stop means by said running course of yarn and being constructed to move of its own weight into engagement with said element to initiate the operation of the stop means upon breakage or termination of said yarn, said first arm being pivotally mounted with respect to said second arm, a pendant member arranged to move said first arm to initiate the stopping means independently of said second arm, and means movable by the growth of the package being wound on said spindle and arranged to engage with said pendant member substantially only after a predetermined size of package has been attained to initiate the stopping means.

4. In a winding machine, a winding spindle, a traverse frame, means for pivotally swinging said traverse frame as the winding proceeds, a rotatable element, means for rotating said element, 5 means for stopping said machine, a pivotally suspended member having an arm movable into engagement with said element to initiate the operation of said stop means and having a second arm in engagement with the running course of yarn, said member being normally withheld from movement to initiate operation of the stopping means by said running course of yarn and being constructed to move of its own weight into engagement with said element to initiate operation of the stopping means upon breakage or termination of said yarn, said first arm being pivotally mounted with respect to said second arm, a pendant member arranged to move said first arm to 10 initiate the stopping means independently of said second arm, said pendant member being arranged in the path of swinging of said traverse frame so that it is engaged thereby substantially only after a predetermined size of package has been attained and then moved into stopping position.
